Inventor:

Fredric Kettler

UNITED STATES PATENT OFFICE.

FREDERIC KETTLER, OF MILWAUKEE, WISCONSIN.

IMPROVEMENT IN ROTARY PUMPS.

Specification forming part of Letters Patent No. 35,452, dated June 3, 1862.

To all whom it may concern:

Be it known that I, FREDERIC KETTLER, of Milwaukee, State of Wisconsin, have invented a new and Improved Rotary Pump; and I do hereby declare that the following is a full and exact description thereof, reference being had to the accompanying drawings and the letters of reference marked thereon.

The purpose of my invention is to construct a perfect air-tight and durable pump.

Figure 1 is a profile view of this pump, showing all the different parts of it. Fig. 2 is a top view of the same.

Axle A is fastened in plate B. This plate B has sections cut out from each side, in which pistons C move. These pistons C are provided with cog-rollers D, which are placed between pistons C and plate B. The purpose of said cog-rollers is to ease the motion of piston C. Abutments E of pistons C are constructed of brass or other suitable material and fastened to the pistons C by means of hinges. Plates E' E partially cover the pistons C and forward cog-rollers, D D.

F' is an elevation in which a spring, F, presses firmly against plate B to prevent the escape of water.

G is a volute spring around axle A, forming a packing thereon.

H is the outer cylinder of this pump, and I the lid of this pump, provided with a box for axle A.

R is the induction-pipe, and L the eduction-pipe. This latter is provided with the small hole m, which lets out all the water standing above that point, and so prevents its freezing. This hole is provided with a spring, which, through the pressure of the water, in case the pump is to throw the stream a great distance, closes it.

What I claim as my invention, and desire to secure by Letters Patent, is—

1. The combination of cog-rollers G, with pistons C, and plate B, as shown and described.

2. The abutments E and plates E', and pistons C, as combined and arranged with the whole apparatus.

3. The elevation F', in combination with the spring F, arranged and combined with the apparatus, as described.

4. The volute spring G, arranged in the manner and for the purpose specified, in combination with the apparatus, forming a packing around the axle A.

5. Valve m, in combination with the apparatus, in the manner and for the purpose set forth.

FREDERIC KETTLER.
